ABSTRACT

The present invention relates to an improved method of continuously vaporizing and superheating a stream of liquefied cryogenic fluid wherein the stream is vaporized and then superheated to a desired temperature level by exchange of heat with gas turbine exhaust gases. By the present invention, the vaporized cryogenic fluid is passed in heat exchange relationship with the turbine exhaust gases in successive serially connected heat exchange stages. A quantity of liquefied cryogenic fluid is combined with the vaporized cryogenic fluid passing through each of the stages so that the liquefied cryogenic fluid is vaporized and the resulting combined vapor is cooled prior to passing through the next successive heat exchange stage. By the present invention, smaller and less expensive heat exchange apparatus is required and the maximum heating capacity of the turbine exhaust gases is utilized for vaporizing and superheating the cryogenic fluid.

METHOD OF CONTINUOUSLY VAPORIZING AND SUPERHEATING LIQUEFIED CRYOGENIC FLUID

BACKGROUND OF THE INVENTION

1. Field of the Invention

The present invention relates generally to an improved method of continuously vaporizing and superheating liquefied cryogenic fluid, and more particularly, but not by way of limitation, to a method of vaporizing and superheating a stream of liquefied cryogenic fluid wherein the fluid is heat exchanged with turbine exhaust gases.

2. Description of the Prior Art

Many various methods and systems have been developed for vaporizing and superheating cryogenic fluids. The term "cryogenic fluid" is used herein to mean those fluids which exist in the liquid state at a temperature below about -150° F at pressures up to about 1000 psia, e.g., liquefied natural gas.

In recent years the use of liquefied natural gas as a source of fuel in areas where natural gas is unavailable has increased. In these areas, a continuous stream of liquefied natural gas is vaporized, superheated and distributed by pipeline to points of use. Many various methods and systems have been developed and used for vaporizing and superheating liquefied cryogenic fluids. Generally, the methods and systems have required elaborate heating equipment involving high operating costs. Recently, in order to improve the economics of such systems, it has been proposed to utilize ambient water as the heating medium for vaporizing and superheating liquefied natural gas. The term "ambient water" is used herein to mean water contained in large bodies such as oceans, lakes, rivers, etc. Further, in order to vaporize and superheat a stream of liquefied cryogenic fluid utilizing ambient water without incurring a detrimental temperature drop in the ambient water and in order to generate power for pumping the liquefied cryogenic fluid and ambient water streams, a method utilizing ambient water to vaporize the stream of liquefied cryogenic fluid and utilizing turbine exhaust gases for superheating the vaporized cryogenic fluid to a desired level of superheat was developed and is described in my co-pending application Ser. No. 150,448 filed June 7, 1971. While methods and systems utilizing ambient water and turbine exhaust gas heat exchange for vaporizing and superheating a liquefied cryogenic fluid stream are highly advantageous economically, in certain applications inadequate temperature control of the superheated cryogenic fluid stream may be experienced.

By the present invention an improved method of continuously vaporizing and superheating a stream of liquefied cryogenic fluid wherein the stream is vaporized and then superheated to a desired temperature level by exchange of heat with gas turbine exhaust gases is provided wherein maximum temperature control of the superheated cryogenic fluid is provided and utilization of the maximum heating capacity of the turbine exhaust gases is achieved.

SUMMARY OF THE INVENTION

The present invention relates to an improved method of continuously vaporizing and superheating a stream of liquefied cryogenic fluid wherein the stream is vaporized and then superheated to a desired tempera-

ture level by exchange of heat with gas turbine exhaust gases. By the present invention, the vaporized cryogenic fluid is passed in heat exchange relationship with the turbine exhaust gases in successive serially connected heat exchange stages. Quantities of liquefied cryogenic fluid are combined with the vaporized cryogenic fluid passing through each of said stages so that the liquefied cryogenic fluid is vaporized and the resulting combined vapor is cooled prior to passing through the next successive heat exchange stage thereby utilizing the maximum heating capacity of said turbine exhaust gases.

It is, therefore, a general object of the present invention to provide an improved method of continuously vaporizing and superheating liquefied cryogenic fluid.

A further object of the present invention is the provision of an improved method of vaporizing and superheating a liquefied cryogenic fluid stream wherein the cryogenic fluid stream is heated and vaporized by exchange of heat with ambient water and then superheated to a desired temperature level by exchange of heat with turbine exhaust gases.

Yet a further object of the present invention is the provision of an improved method of vaporizing and superheating a stream of liquefied cryogenic fluid by exchange of heat with turbine exhaust gases wherein smaller and less expensive heat exchange apparatus is required and the maximum heating capacity of the turbine exhaust gases is utilized.

Other and further objects of the present invention will be apparent from the following detailed description of the presently preferred embodiments of the invention when read in conjunction with the accompanying drawings.

BRIEF DESCRIPTION OF THE DRAWINGS

FIG. 1 illustrates, in diagrammatic form, one system which may be utilized for carrying out the improved method of the present invention, and

FIG. 2 illustrates, in diagrammatic form, a preferred arrangement of heat exchange and gas turbine apparatus for the system of FIG. 1.

DESCRIPTION OF THE PREFERRED EMBODIMENTS

Referring now to the drawings, and particularly to FIG. 1, one system which may be utilized for carrying out the method of the present invention is illustrated in diagrammatic form, and generally designated by the numeral 10. A stream of liquefied cryogenic fluid from a conventional liquefied cryogenic fluid storage tank 12, or other source, is pumped by pump 14 into one or more ambient water-cryogenic fluid heat exchangers 18 by way of conduit 16. The heat exchangers 18 may be a plurality of conventional open rack water heat exchangers or other conventional heat exchangers suitable for use with large volumes of ambient water. A conduit 20 having one end disposed beneath the surface of the ambient water source is connected to one or more conventional water pumps 22. The discharge of the pumps 22 is connected by a conduit 24 to the water inlet connection of the heat exchangers 18. After passing through the exchangers 18, the water is returned or recycled to its source by way of a conduit 26. As the liquefied cryogenic fluid stream passes

through the heat exchangers 18, heat is exchanged between it and the water passing therethrough causing the cryogenic fluid stream to be heated and vaporized. The volume of water passed through the exchangers 18 is controlled so that the temperature drop in the water is maintained at a level meeting thermal pollution standards, e.g., 1° to 2° F.

A pair of conventional gas turbines 28 and 30 are provided, each of which generates large volumes of hot exhaust gases through the combustion of fuel and air. Two gas turbines are provided in order to insure that one of the turbines is operable at all times and that a continuous stream of vaporized and superheated natural gas is produced. However, as will be described further hereinbelow, both of the gas turbines 28 and 30 are continuously operated.

The exhaust gases generated by the gas turbine 28 are conducted by way of a conduit or duct 32 to a heat exchanger 34. The cryogenic fluid stream heated and vaporized in the heat exchangers 18 exits the exchangers 18 by way of a conduit 36. The conduit 36 is connected to a pair of conduits 38 and 40 and conventional controls are provided therein (not shown) for dividing the vaporized cryogenic fluid stream into two portions, the first portion passing into conduit 38 and the second portion passing into the conduit 40. The first portion passes by way of conduit 38 to a pair of conduits 42 and 44 and conventional controls are provided (not shown) for dividing the first portion of the vaporized cryogenic fluid into two streams which pass through the conduits 42 and 44.

The stream of vaporized cryogenic fluid passing through the conduit 42 is conducted to heating tubes disposed within the heat exchanger 34. While passing through the heating tubes within the exchanger 34, heat is exchanged between the turbine exhaust gases and the vaporized cryogenic fluid stream so that the cryogenic fluid stream is heated to a predetermined temperature level. In addition, as will be described further hereinbelow, a quantity of liquefied cryogenic fluid is combined with the vaporized cryogenic fluid stream passing through the heat exchanger 34 so that the maximum heating capacity of the turbine exhaust gases is utilized. The superheated cryogenic fluid vapor exiting the heat exchanger 34 passes into a conduit 48 connected thereto.

The exhaust gases generated by the turbine 30 are conducted by way of a conduit or duct 50 to a heat exchanger 52. The stream of vaporized cryogenic fluid passing through the conduit 44 is conducted to heating tubes disposed within the heat exchanger 52. While passing through the exchanger 52, heat is exchanged between the turbine exhaust gases and the vaporized cryogenic fluid stream so that the cryogenic fluid stream is heated to a predetermined level of superheat. As in the case of heat exchanger 34, a quantity of liquefied cryogenic fluid is combined with the cryogenic fluid vapor passing through the heat exchanger 52 and the resultant superheated cryogenic fluid exits the heat exchanger 52 by way of a conduit 56. The spent turbine exhaust gases exit the exchangers 34 and 52 by way of conduits or ducts 58 and 60 from where the exhaust gases are vented to the atmosphere.

The second portion of the vaporized cryogenic fluid from the exchangers 18 passes through the conduit 40

to a pair of conduits 62 and 64. Conventional controls are provided in the conduits 62 and 64 (not shown) for dividing the second portion of vaporized cryogenic fluid stream into two streams, one of which passes through the conduit 64 and the other through the conduit 62. The stream of vaporized cryogenic fluid passing through the conduit 64 is conducted to a plurality of heating tubes disposed within a heat exchanger 68. Combustion air for the turbine 28 is drawn from the atmosphere by way of a conduit 70 through the heat exchanger 68 and then by way of a conduit 72 into the gas turbine 28. While passing through the heat exchanger 68, heat is exchanged between the stream of vaporized cryogenic fluid and the combustion air so that the combustion air is cooled. As has been heretofore known, the cooling of the combustion air utilized in the gas turbine 28 is advantageous in that the power output of the turbine 28 is increased accordingly. After passing through the heat exchanger 68 the vaporized cryogenic fluid stream is conducted by a conduit 74 to a conduit 76.

The stream of vaporized cryogenic fluid passing through the conduit 62 is conducted to a plurality of heating tubes disposed within a heat exchanger 80. Combustion air is drawn from the atmosphere by way of a conduit 82 through the heat exchanger 80 and then by way of the conduit 84 to the gas turbine 30. The vaporized cryogenic fluid stream exiting the exchanger 80 is conducted by way of a conduit 86 to the conduit 76 where it is combined with the stream of vaporized cryogenic fluid passing through the conduit 76 from the heat exchanger 68. As will be described further herein, quantities of liquefied cryogenic fluid are combined with the vaporized cryogenic fluid streams passing through the exchangers 68 and 80 to prevent the formation of excessive quantities of ice in the exchangers. The combined vaporized cryogenic fluid stream is conducted by the conduit 76 to a conduit 88.

The conduits 48 and 56 connected to the heat exchangers 34 and 52 respectively are connected to the conduit 88. Thus, the superheated cryogenic fluid streams passing from the exchangers 34 and 52 are combined in the conduit 88 with the stream of vaporized cryogenic fluid passing thereto by way of conduit 76. From the conduit 88 the composite stream of vaporized and superheated cryogenic fluid is conducted by a conduit 90 to a vapor-liquid contactor 92. A stream of liquefied cryogenic fluid is conducted to the contactor 92 by way of a conduit 94 connected thereto and connected to the conduit 16. The quantity of liquefied cryogenic fluid passed to the contactor 92 by way of the conduit 94 is controlled such that the resultant combined stream exiting the contactor 92 by way of the conduit 96 is at a desired specific temperature. That is, the contactor 92 is utilized to combine a controlled quantity of liquefied cryogenic fluid with the stream of superheated cryogenic fluid passing therethrough so that the combined stream is produced at a desired temperature. Thus, in the event of operational fluctuations in the system 10 and load changes on the turbines 28 and 30, the temperature of the vaporized and superheated cryogenic fluid stream produced is maintained at a constant level. From the conduit 96 the vaporized and superheated cryogenic fluid is conducted to a point of use or distribution. Fuel

for the gas turbines 28 and 30 may be drawn from the composite vaporized and superheated cryogenic fluid stream passing through the conduit 88 by way of a conduit 98 attached thereto.

Referring now to FIG. 2, a preferred arrangement of the gas turbines 28 and 30 and heat exchangers 34, 52, 68 and 80 is illustrated.

As shown in FIG. 2, the stream of cryogenic fluid heated and vaporized in the heat exchangers 18 is passed by way of conduit 36 to a pair of conduits 38 and 40. The conduit 40 leads a portion of the vaporized cryogenic fluid to a pair of conduits 62 and 64. The conduit 64 leads a stream of the cryogenic fluid vapor to the heat exchanger 68 associated with the gas turbine 28. As previously described, atmospheric air is drawn through the heat exchanger 68 by way of the conduit 70 wherein it is cooled by heat exchange with the vaporized cryogenic fluid, and then passed by way of conduit 72 to the turbine 28. A conventional temperature controller 100 is disposed in the air conduit or duct 72. The temperature controller 100 senses the temperature of the input air to the turbine 28 and opens or closes a conventional control valve 102 disposed in the conduit 64 accordingly. That is, if the temperature of the air passing through the conduit 72 is too high, the temperature controller 100 opens the control valve 102 so that more cryogenic fluid vapor is passed through the heat exchanger 68 thereby providing additional cooling to the air, and vice versa.

The heating tubes disposed within the heat exchanger 68 are arranged in successive serially connected stages. That is, a first bank of heating tubes 104 is provided connected to the conduit 64. A second tube bank 106 is provided connected externally of the exchanger 68 in series with the tube bank 104 and a third tube bank 108 is connected externally of the exchanger 68 to the tube bank 106. The cryogenic fluid vapor stream exiting the heat exchanger 68 passes by way of conduit 74 into the conduit 76 as previously described. Shutoff valves 110 and 112 are disposed in the conduits 64 and 74 respectively.

A quantity of liquefied cryogenic fluid is combined with the cryogenic fluid vapor stream passing through the tube bank 106 and a quantity of liquefied cryogenic fluid is combined with the vapor stream passing through the tube bank 108 in order to cool the resulting combined streams prior to their passage through the tube banks. This "stage injection" of liquefied cryogenic fluid is used to maintain the temperature of the cryogenic fluid vapor stream passing through the exchanger 68 at a relatively constant level thereby preventing the formation of excessive ice on the outside surfaces of the heating tubes. This method of cooling the turbine combustion air is described in detail in my U.S. Pat. No. 3,552,134 dated Jan. 5, 1971.

As shown in FIG. 2, the liquefied cryogenic fluid combined in the exchanger 68 is conducted by way of a conduit 114 to a header 116. The conduit 114 is connected to a source of liquefied cryogenic fluid which may be the conduit 16 downstream of the pump 14. A conduit 118 is connected to the header 116 and to the outlet of the tube bank 104 of the exchanger 68. A conventional temperature control assembly 120 is disposed in the conduit 118 for controlling the quantity of liquefied cryogenic fluid injected. A block valve 122 is

provided in the conduit 118. A conduit 124 is connected to the header 116 and to the outlet of the tube bank 106. A temperature control assembly 126 and block valve 128 are disposed in the conduit 124.

As will be apparent from FIG. 2, the heat exchanger 80 associated with the gas turbine 30 is identical to the heat exchanger 68 described above. A portion of the cryogenic fluid vapor from the conduit 40 passes by way of the conduit 62 to the heat exchanger 80. A temperature control valve 132 disposed within the conduit 62 is operably connected to a conventional temperature controller 134 disposed in the air conduit or duct 84. Successive serially connected tube banks 130, 138 and 140 are provided in the heat exchanger 80 and a block valve 142 is disposed in the outlet conduit 86 which is connected to the conduit 76. Conduits 144 and 146 are provided connected to the liquefied cryogenic fluid header 116 and to the tube banks 130 and 138. Temperature control assemblies 148 and 150 and block valves 152 and 154 are provided in the conduits 144 and 146 respectively.

The portion of the vaporized cryogenic fluid passing through conduit 38 is divided between the conduits 42 and 44 as previously described. As shown in FIG. 2, the conduit 42 is connected to heating tubes disposed within the heat exchanger 34 associated with the turbine 28. The conduit 44 is connected to heating tubes disposed within the heat exchanger 52 associated with the turbine 30. As described above for the heat exchangers 68 and 80, each of the heat exchangers 34 and 52 include banks of heating tubes arranged in successive serially connected stages. That is, the heat exchanger 34 includes three serially connected tube banks 156, 158 and 160 and the heat exchanger 52 includes three serially connected tube banks 166, 168 and 170. The conduit 42 is connected to the inlet of the tube bank 156 of the exchanger 34 and the outlet of the tube bank 160 thereof is connected by the conduit 48 to the conduit 88. The conduit 44 is connected to the inlet of the tube bank 166 of the exchanger 52 and the outlet of the tube bank 170 thereof is connected by the conduit 56 to the conduit 88. Quantities of liquefied cryogenic fluid are injected or combined with the cryogenic fluid vapor passing through each stage or tube bank of each of the exchangers 34 and 52 so that the resulting composite vapor streams are cooled and the maximum heating capacity of the exhaust gases passing through the heat exchangers 34 and 52 are utilized. For this purpose, a pair of conduits 162 and 164 are connected to the header 116 and to the outlets of the tube banks 156 and 158 of the exchanger 34 and a pair of conduits 172 and 174 connect the header 116 to the outlets of the tube banks 166 and 168. Conventional temperature control assemblies 176 and 178 and block valves 180 and 182 are disposed in the conduits 162 and 164 respectively. Similarly, conventional temperature controllers 184 and 186 and block valves 188 and 190 are disposed in the conduits 172 and 174 respectively. Shutoff or block valves 192, 194, 196 and 198 are disposed in the conduits 42, 48, 44 and 56 respectively.

The turbines 28 and 30 drive conventional electric generators 200 and 202 respectively.

OPERATION OF THE SYSTEM 10

The system 10 includes two conventional gas turbines 28 and 30 which provide power for operating two conventional electric generators 200 and 202. The primary purpose of including two gas turbines and electric generators is to provide a standby turbine for providing hot exhaust gases and electric power in the event one of the turbines fails thereby insuring the production of a continuous stream of vaporized and superheated cryogenic fluid. However, in operation of the system 10, both of the gas turbines 28 and 30 are continuously operated. The electric power output of one of the electric generators 200 or 202 is advantageously used for operating the liquefied cryogenic fluid pumps 14 and the ambient water pumps 22. The electric power output from the other electric generator may be sold to a power company or other electric power consumer.

The system 10 is designed so that the required minimum rate of vaporized and superheated cryogenic fluid may be produced utilizing the exhaust gases generated from one of the turbines 28 and 30. Thus, if one of the turbines fails and is taken out of service, the exhaust gases generated by the other turbine are used to vaporize and superheat the required minimum rate of cryogenic fluid and the power output of the electric generator associated therewith is utilized to operate the pumps 14 and 22.

During normal operation of the system 10, a stream of liquefied cryogenic fluid is pumped by the pump 14 through the ambient water cryogenic fluid heat exchangers 18 by way of conduit 16. While passing through the exchangers 18 the stream of cryogenic fluid is heated and vaporized. As described above, the vaporized stream is split into two portions, the major portion of which passes by way of conduit 38 to the conduits 42 and 44 where it is divided into two portions, one portion passing by way of conduit 42 through the heat exchanger 34 and the other portion passing by way of conduit 44 through the heat exchanger 52. While passing through the exchangers 34 and 52 the vaporized cryogenic fluid streams are combined with quantities of liquefied cryogenic fluid and the combined streams are superheated to desired temperature levels. The superheated streams then pass by way of conduits 48 and 56 into the conduit 88. The particular quantities of liquefied cryogenic fluid injected in the heat exchangers 34 and 52 is controlled by the temperature control assemblies 176, 178, 184 and 186. That is, the temperature controllers 176 and 178 associated with the heat exchanger 34 are set so that the temperature of the combined stream exiting the exchanger by way of conduit 48 is at a desired level, and the controllers 184 and 186 associated with the exchanger 52 are set similarly. Thus, during normal operation of the system 10, the heat exchangers 34 and 52 are each handling one-half the stream of cryogenic fluid heated and vaporized in the ambient water exchangers 18. In order to utilize the full heating capacity of the exhaust gases produced by the turbines 28 and 30, liquefied cryogenic fluid is injected into the exchangers 34 and 52.

The minor portion of the vaporized cryogenic fluid stream from the exchangers 18 passes by way of conduit 40 to the conduits 62 and 64 wherein it is divided into two portions, one of which passes through the heat

exchanger 68 and the other through the heat exchanger 80. As described above, the heat exchangers 68 and 80 cool the input combustion air to the turbines 28 and 30 respectively. The heated combined vaporized cryogenic fluid streams exiting the exchangers 68 and 80 are combined in the conduit 76 and conducted to the conduit 88 where they combine with the superheated cryogenic fluid streams from the exchangers 34 and 52. The composite stream is conducted by conduit 90 to the contactor 92 wherein a small additional quantity of liquefied cryogenic fluid is combined with the composite stream to trim out the temperature of the stream. From the contactor 92, the stream is conducted to a point of use or distribution.

As shown in FIG. 2, the portion of vaporized cryogenic fluid from the exchangers 18 which is routed to the combustion air coolers 68 and 80 is controlled by the temperature controllers 100 and 134 and control valves 102 and 132. That is, the quantity of vaporized cryogenic fluid passed to the exchangers 68 and 80 is increased or decreased by the temperature controllers 100 and 102 in accordance with the temperatures of the combustion air streams passing to the turbines 28 and 30. The remaining portion of the vaporized cryogenic fluid stream is divided substantially equally between conduits 42 and 44. The division of the stream may be accomplished through the utilization of conventional flow controllers 43 and 45 disposed in the conduits 42 and 44. As will be understood by those skilled in the art, many various other control apparatus may be used for dividing the vaporized cryogenic fluid stream exiting the heat exchangers 18 into the various portions required.

In the event one of the turbines 28 or 30 either fails or must be shut down for other reasons, the required minimum rate of vaporized and superheated cryogenic fluid is produced by the system 10. Specifically, let it be assumed that the turbine 28 is shut down. Upon shut down of the turbine 28, the block valves disposed in the conduits to and from the heat exchangers 68 and 34 are closed. That is, the valves 110, 112, 122 and 128 associated with the exchanger 68 are closed, and the valves 180, 182, 192 and 194 associated with the exchanger 34 are closed. Additionally, the flow of liquefied cryogenic fluid to the exchanger 52 by way of the conduits 172 and 174 is reduced or stopped. Thus, in operation of the system 10 with the turbine 28 and relating heat exchangers shut down, the stream of vaporized cryogenic fluid exiting the ambient water heat exchangers 18 passes by way of the conduit 36 to the conduit 38 and 40. A minor portion of the vaporized cryogenic fluid stream passes by way of the conduit 40 to the heat exchanger 80 wherein it is utilized to cool the input combustion air to the turbine 30 in the same manner as described above. The major portion of the vaporized cryogenic fluid passes by way of conduit 38 to the heat exchanger 52. As the vaporized cryogenic fluid stream passes through the exchanger 52 it is superheated to as high a temperature as possible without the addition of liquefied cryogenic fluid. Normally, the system 10, and specifically the heat exchangers 34 and 52 are designed so that when the entire superheating load is handled by one of the exchangers 34 or 52, the stream of cryogenic fluid is heated to a temperature only slightly higher than the desired tempera-

ture. In order to trim out the temperature, i.e., reduce the temperature of the cryogenic fluid stream to a desired level and allow for operational fluctuations and load changes, the stream is passed to the contactor 92 (FIG. 1) wherein a quantity of liquefied cryogenic fluid is combined therewith as described above. The quantity of liquefied cryogenic fluid combined in the contactor 92 is controlled by conventional temperature control instruments (not shown) so that the resulting combined stream exiting the contactor 92 by way of the conduit 96 is at the desired temperature.

Thus, by the present invention, both of the turbines 28 and 30 are continuously operated with the maximum heating capacity of the turbine exhaust gases being utilized to vaporize and superheat cryogenic fluid. Further, the electric power output of the generators associated with the turbines is utilized to operate the various pumps of the system 10, with a portion thereof being sold to an outside consumer or otherwise utilized. In the event of a turbine shut down, the required vaporized and superheated cryogenic fluid rate is produced by the system 10.

As will be understood, the present invention wherein controlled quantities of liquefied cryogenic fluid are stage combined with a vaporized cryogenic fluid stream being superheated by exchange of heat with turbine exhaust gases is not limited to use in the specific system described above and may be utilized to advantage in a variety of systems. By the use of the present invention, the surface area required for the turbine exhaust gas heat exchanger is reduced due to the resulting higher log mean temperature difference achieved.

In order to present a clear understanding of the present invention, the following example is given:

EXAMPLE

Let it be assumed that the system 10 must be capable of producing a 929 mmscf/day stream of natural gas at a temperature of 60° F. During normal operation, a 1,496,500 lb/hr stream of liquefied natural gas (LNG) at a temperature of -260° F is pumped from the storage tank 12 by the pump 14 to the heat exchangers 18 at a pump discharge pressure of 1000 psig. A 476,000 gpm stream of ambient water at a temperature of 70° F is pumped by the pumps 22 through the heat exchangers 18. For a 2° temperature drop in the water, 476,380,000 btu/hr are transferred from the ambient water stream to the LNG stream causing the LNG to be vaporized and heated to a temperature of 0° F. The vaporized natural gas stream at a temperature of 0° F is conducted by the conduit 36 to the conduits 38 and 40. A 588,560 lb/hr portion of the natural gas is passed by way of conduit 40 to the conduits 62 and 64. A 294,280 lb/hr stream is passed by way of the conduit 64 through the heating tubes disposed within the heat exchanger 68, and a 294,280 lb/hr stream is passed by way of the conduit 62 through the heating tubes disposed in the heat exchanger 80. Each of the exchangers 68 and 80 are operated in an identical manner. That is, a 767,800 lb/hr stream of combustion air at a temperature of 80° F (50 percent saturated with water) is drawn through the conduits 70 and 82 to the exchangers 68 and 80 respectively. As the combustion air stream is passed through the heat exchangers 68 and 80, 12,190,000 btu/hr of heat is transferred from the air to the natural

gas streams, causing the air to be cooled to a temperature of 40° F. 35,456 lb/hr of LNG are combined with the natural gas passing through the heat exchangers 68 and 80. That is, 35,456 lb/hr of LNG are combined with the natural gas passing through the tube banks 104, 106 and 108 of the exchanger 68 and a 329,736 lb/hr combined stream of natural gas exits the heat exchanger 68 at a temperature of 3° F. 35,456 lb/hr of LNG are combined with the natural gas stream passing through the tube banks 130, 138 and 140 of the exchanger 80 and a 329,736 lb/hr combined stream of natural gas exits the heat exchanger 80 at a temperature of 3° F. The natural gas streams from the exchangers 68 and 80 are combined and a 659,472 lb/hr stream of natural gas at a temperature of 3° F passes by way of the conduit 76 to the conduit 88.

A 907,940 lb/hr portion of the natural gas stream exiting the exchangers 18 at a temperature of 0° F passes by way of the conduit 38 to the conduits 42 and 44. 453,970 lb/hr of the natural gas passes by way of conduit 42 through the exchanger 34. 220,878 lb/hr of LNG are combined with the natural gas in the exchanger 34, which LNG is vaporized and the resulting combined stream (674,848 lb/hr) is heated to a temperature of 150° F.

453,970 lb/hr of the natural gas at 0° F is passed by way of the conduit 44 through the heat exchanger 52. 220,878 lb/hr of LNG are combined with the natural gas in the heat exchanger 52 and the resulting combined stream of 674,848 lb/hr exits the exchanger 52 at a temperature of 150° F.

A 780,000 lb/hr stream of exhaust gases at a temperature of 950° F is produced by each of the turbines 28 and 30. The exhaust gases are conducted from the turbines 28 and 30 by the ducts 32 and 50 respectively to the exchangers 34 and 52. 133,000,000 btu/hr are transferred from the turbine exhaust gases to the natural gas stream and injected LNG, and the spent exhaust gases exit the exchangers 34 and 52 at temperatures of 300° F. The superheated natural gas streams from the exchangers 34 and 52 pass by way of the conduits 48 and 56 respectively into the conduit 88 where they combine with the natural gas stream entering the conduit 88 by way of the conduit 76. The resultant composite stream (2,009,168 lb/hr) at a temperature of 100° F is conducted by way of the conduit 90 to the contactor 92. 135,016 lb/hr of liquefied natural gas is conducted to the contactor 92 by way of the conduit 94 and the resultant natural gas stream exits the system 10 at a rate of 1,146,000,000 scf/day and a temperature of 60° F by way of the conduit 89.

In operation of the system 10 with one of the turbines 28 or 30 shut down, for example, with the turbine 28 shut down, the natural gas stream exiting the exchangers 18 at a temperature of 0° F is divided into major and minor portions, the minor portion (294,280 lb/hr) passing by way of the conduits 40 and 62 to the heat exchanger 80. A 329,736 lb/hr stream of natural gas exists the exchanger 80 by way of the conduits 86 and 76 at a temperature of 3° F. The major portion of the natural gas stream (1,202,220 lb/hr) at a temperature of 0° F passes by way of the conduits 38 and 44 to the turbine exhaust gas heat exchanger 52 associated with the turbine 30. While passing through the heat exchanger 52, 133,000,000 btu/hr is transferred from

the turbine exhaust gases to the natural gas stream causing the natural gas stream to be superheated to a temperature of 175° F. Spent turbine exhaust gases at a temperature of 300° F are conducted from the exchanger 52 by way of duct 60. The superheated natural gas stream from the exchanger 52 passes by way of the conduit 56 to the conduit 88 wherein it is combined with the natural gas passing into the conduit 88 by way of the conduit 76 making a total composite stream of 1,531,956 lb/hr at a temperature of 140° F. The composite stream is passed from the conduit 88 by way of the conduit 90 to the contactor 92. A 205,971 lb/hr LNG stream is passed by way of the conduit 94 to the contactor 92 wherein it intimately mixes with the natural gas stream. While within the contactor 92, heat is transferred from the superheated natural gas stream to the LNG stream causing the LNG to be vaporized and combined with the natural gas stream resulting in a 929 mmscf/day stream of natural gas at a temperature of 60° F.

The present invention, therefore, is well adapted to carry out the objects and attain the ends and advantages mentioned as well as those inherent therein. While presently preferred systems for carrying out the method of the present invention are given for the purpose of disclosure, numerous changes can be made which will readily suggest themselves to those skilled in the art and which are encompassed within the spirit of the invention disclosed herein.

What is claimed is:

1. In a method of continuously vaporizing and superheating a stream of liquefied cryogenic fluid wherein the stream is vaporized and then superheated to a desired temperature level by exchange of heat with gas turbine exhaust gases, the improvement comprising:

passing said vaporized cryogenic fluid in heat exchange relationship with said turbine exhaust gases in successive serially connected heat exchange stages; and

combining a quantity of liquefied cryogenic fluid with the vaporized cryogenic fluid passing through each of said stages so that the liquefied cryogenic fluid is vaporized and the resulting combined vapor is cooled prior to passing through the heat exchange stage thereby utilizing the maximum heating capacity of said turbine exhaust gases.

2. The method of claim 1 wherein the liquefied cryogenic fluid is liquefied natural gas.

3. In a method of continuously vaporizing a stream of liquefied cryogenic fluid wherein the stream is vaporized and then superheated by exchange of heat with gas turbine exhaust gases, at least a portion of the vaporized cryogenic fluid stream being passed in heat exchange relationship with the turbine input air so that said air is cooled and the power output of the turbine increased, the improvement comprising:

dividing said stream of liquefied cryogenic fluid into first and second streams;

passing said first stream of liquefied cryogenic fluid in heat exchange relationship with a stream of ambient water so that said first stream is heated and vaporized;

passing said heated and vaporized stream in heat exchange relationship with said turbine exhaust gases in successive serially connected heat exchange stages; and

combining portions of said second stream of liquefied cryogenic fluid with the vaporized cryogenic fluid passing through each of said turbine exhaust gases heat exchange stages so that the liquefied cryogenic fluid is vaporized and the resulting combined stream is cooled prior to passing through the stage thereby utilizing the maximum heating capacity of said turbine exhaust gases to heat the combined stream to a desired level of superheat.

4. The method of claim 3 which is further characterized to include the steps of:

passing the portion of the vaporized cryogenic fluid stream heat exchanged with said turbine input air in successive serially connected heat exchange stages with said air; and

combining a portion of said second stream of liquefied cryogenic fluid with the vaporized cryogenic fluid passing through each of said input air heat exchange stages so that the resulting combined stream is cooled prior to passing through the stage thereby maintaining the formation of ice from water vapor contained in said air at a minimum.

5. The method of claim 4 wherein the liquefied cryogenic fluid is liquefied natural gas.

6. The method of claim 5 wherein a portion of the produced vaporized and superheated natural gas is utilized as fuel for said turbine.

7. In a method of continuously vaporizing a stream of liquefied cryogenic fluid wherein the stream is vaporized and then superheated by exchange of heat with gas turbine exhaust gases, at least a portion of the vaporized cryogenic fluid stream being passed in heat exchange relationship with the turbine input air so that said air is cooled and the power output of the turbine increased, the improvement comprising:

a. dividing said stream of liquefied cryogenic fluid into first, second and third streams;

b. passing said first stream of liquefied cryogenic fluid in heat exchange relationship with a stream of ambient water so that said first stream is heated and vaporized;

c. passing said heated and vaporized stream in heat exchange relationship with said turbine exhaust gases in successive serially connected heat exchange stages;

d. combining portions of said second stream of liquefied cryogenic fluid with the vaporized cryogenic fluid passing through each of said turbine exhaust gases heat exchange stages so that the liquefied cryogenic fluid is vaporized and the resulting combined stream is cooled prior to passing through the stage thereby utilizing the maximum heating capacity of said turbine exhaust gases; and

e. combining said third stream of liquefied cryogenic fluid with the stream of heated and vaporized cryogenic fluid from step (d) so that the resultant composite vapor stream is produced at a desired temperature.

8. The method of claim 7 which is further characterized to include the steps of:

passing the portion of the vaporized cryogenic fluid stream heat exchanged with said turbine input air in successive serially connected heat exchange stages with said air; and

combining a portion of said second stream of liquefied cryogenic fluid with the vaporized cryogenic fluid passing through each of said input air heat exchange stages so that the resulting combined stream is cooled prior to passing through the stage thereby maintaining the formation of ice

from water vapor contained in said air at a minimum.

9. The method of claim 8 wherein the liquefied cryogenic fluid is liquefied natural gas.
